(57) **CLAIM**

The ornamental design for a susceptor cover as shown and described.

DESCRIPTION

FIG. 1 is a perspective view of a susceptor cover showing our new design,

FIG. 2 is a front elevational view thereof,

FIG. 3 is a rear elevational view thereof,

FIG. 4 is a right side elevational view thereof,

FIG. 5 is a left side elevational view thereof,

FIG. 6 is a top plan view thereof, a bottom plan view being a mirror image thereof; and,

FIG. 7 is an enlarged end face sectional view taken along line 7-7 of FIG. 2.

The broken lines in FIG. 2 are for the purpose of illustrating portions of the susceptor cover in FIG. 7 and form no part of the claimed design.
